ATTORNEYS

UNITED STATES PATENT OFFICE.

JOSEPH R. POLIZZI, OF NEW ORLEANS, LOUISIANA.

FLYING-MACHINE.

1,117,901.

Specification of Letters Patent. Patented Nov. 17, 1914.

Application filed January 27, 1913. Serial No. 744,403.

To all whom it may concern:

Be it known that I, JOSEPH R. POLIZZI, a citizen of the United States, and a resident of New Orleans, in the parish of Orleans and State of Louisiana, have made certain new and useful Improvements in Flying-Machines, of which the following is a specification.

My invention relates to flying machines, my more particular purpose being to improve the stabilizing of the machine while in air and to facilitate the guiding of the machine up and down.

My invention further seeks to promote the safety of the machine in ascending, either at the will of the operator or in case of accident.

My invention further contemplates mechanism for rendering the machine approximately level throughout its entire length whether flying upon a level, ascending or descending.

My invention further contemplates various improvements in the flying machine for the purpose of increasing the general efficiency of the same.

Reference is made to the accompanying drawings forming a part of this specification and in which like letters indicate like parts.

Figure 1 is a side elevation of the machine, the middle portion being partly broken away. Fig. 2 is a fragmentary vertical section on the line 2-2 of Fig. 3. Fig. 3 is a fragmentary plan view of the machine. Fig. 4 is a detail showing partly in section a portion of the steering gear. Fig. 5 is a cross section on the line 5-5 of Fig. 3 looking in the direction of the arrow. Fig. 6 is a fragmentary plan view of one pair of the steering planes. Fig. 7 is a detail showing in perspective certain spars for bracing the planes.

A frame 8 is covered with canvas 9 or other appropriate sheet material and is provided with ogival ends 10 and 11, these parts constituting the body portion of the machine. Light wheels 12 and 13 are provided for the purpose of supporting the machine upon the ground and of enabling it to alight as well as to facilitate the starting of the machine. A front propeller is shown at 14 and a rear propeller at 15, these propellers being mounted upon the propeller shafts 16 and 17 respectively. Two engines 18 and 19 are provided, one for driving each propel-

ler. These engines are located at opposite ends of the machine and are of approximately the same weight for the purpose of balancing each other and rendering the machine comparatively easy to maintain level. A rudder 20 is provided at the rear end of the machine for turning the machine to the right or left. Connected with the rudder is a tiller lever 21; tiller cords 22 are connected with the ends of the tiller lever and are also connected with steering pulleys 23. The tiller cords pass through holes 22* in the covering 9. The steering lever 23 is located in a convenient position to be operated by the foot. The operator's seat is shown at 24 and is located just to the rear of the steering lever 23. Located a little distance in front of the operator's seat 24 is a post 26 provided at its top with a bearing 26*. Extending into this bearing is a revolute shaft 27 carrying an end wheel 28. Secured rigidly upon the shaft 27 is a drum 29. Wound partially upon this drum are cords 30 and 31, these cords being also partially wound upon a drum 32 located within the bottom of the post 26 which is hollow. A shaft 33 extends through the bottom of the post 26 and carries four sprocket wheels 34-34, 35-35 secured rigidly upon it. Engaging the sprocket wheels 34 are sprocket chains 36 and connected with the latter are cords 37, 38 which pass over pulleys 38* and are used for moving the planes as hereinafter described. Other cords 39, 42 are connected with opposite ends of the chains 41 and engage guide pulleys 40, 44 and are connected with the planes 43, 44* as hereinafter described.

The general construction will be understood from Figs. 3 and 6. As these planes are alike it will suffice to describe one of them. Cross pieces 45 which also serve as brac's support bearings 46. The axes upon which the planes rock as centers extend to these bearings. The planes are arranged in pairs as indicated in Fig. 6. Each plane is provided with bars 47 extending the entire width of the plane the adjacent ends of these bars being connected together by a sleeve 48 and set screws 49. Each pair of planes further comprises two rods 50 placed end to end, the adjacent ends being held by a sleeve 51 having generally the form of a cross and provided with set screws 52. Extending above and below the sleeve 51 are spars 53 which project through slots 53*.

There is one of these slots adjacent the front end of the machine and another adjacent the rear end thereof. Connected with each spar 53 are four cords 54 which are connected directly with the edges of the planes and serve as braces for the same. The bars 47 extend through slots 55, 56 provided for this purpose, these slots being of arcuate form as will be understood from Fig. 1. The cords 37-39 42, 38 are secured directly to the rods 47 and by drawing the latter up or down may shift the planes to different inclination relatively to other parts.

The operation of my device is as follows: One or both of the engines 19 may be used, depending upon the power sought to be developed in the machine. For most purposes only one of the engines need be employed. The machine is started and driven forwardly through the air in the usual or any desired manner. When the operator wishes to ascend to a higher level he turns the steering wheel 28. This causes the drum 29 to rotate and by transmitting motion to the cords 30, 31 (see Fig. 2) the drum 32 is caused to turn. The shaft 33 and sprocket wheels 34, 35 upon it being thus caused to rotate, the cords 37, 39, 38 and 42 are drawn in such direction as to tilt the planes 43, 44. It will be noted that the same kind of motion is communicated to the front planes as to the rear planes. That is to say, when the front edges of the front planes are inclined upwardly the front edges of the planes at the rear of the machine are also inclined upwardly to the same extent and when the front edges of either pair of planes are depressed the front edges of the other pair of planes are depressed also to the same degree. By this arrangement the power body is maintained always level whether the car be proceeding parallel with the surface of the earth or be ascending or descending as the same may be. The location of the engines below the pivotal support of the planes insures that the center of gravity is located below the point of support of the machine and the latter is therefore maintained in stable equilibrium. I do not limit myself to the precise arrangement shown as variations may be made

therein without departing from the spirit of my invention as defined by my claims.

I claim:

1. In a flying machine the combination of a frame work provided with a covering having slots of arcuate form disposed upon opposite sides of said body, bearings carried by said frame work, a pair of rods coupled together so as to form practically a continuous rod, said continuous rod being journaled within said bearings, a second pair of rods coupled together to form a practically continuous member, said last mentioned continuous member extending through said slots, wing surfaces carried by said first mentioned continuous rod and said second mentioned continuous rod, said wing surfaces being upon opposite sides of said frame, and means for shifting one of said continuous rods bodily in relation to the other for the purpose of tilting said wing surfaces, one of said rods extending along one edge of each of the wings and the other rod extending along the centers of the wings.

2. In a flying machine the combination of a frame provided with a covering and with a pair of arcuate slots located upon opposite sides of said frame and extending through said covering, said frame being further provided with a slot extending through the top of said covering, bearings carried by said frame, a longitudinal member extending through said bearings and also extending in opposite directions outwardly from said frame, wings mounted upon the outwardly extending portions of said longitudinal member, another longitudinal member extending through said slots and reaching from one of said wings to the other, a spar connected with said first mentioned longitudinal member and crossing the general direction of the length thereof, flexible connections secured to the ends of said spar and also secured to the edges of said wings, said spar extending through said slot in the top of said frame.

JOSEPH R. POLIZZI.
